AUTO TOP WASHING MACHINE

Olin M. Kiggins, Portland, Oreg.

Application June 9, 1930. Serial No. 459,995

5 Claims. (Cl. 15—21)

My invention relates to machines for washing the tops of motor vehicles.

In commercial washing plants for motor vehicles, it is the present practice to move the vehicle along a runway and to wash all the parts, as the top, sides, and wheels, progressively, by workmen stationed at intervals along its course, and who each have their particular duty, the washing of certain parts. By this method, all 10 parts of the vehicle are washed rapidly and efficiently.

However, the washing of the vehicle top by this method has been unsatisfactory because it is relatively inaccessible and the workman is, for this 15 reason, inclined to slight the job. Further, because the grain of the top fabric generally runs longitudinally of the vehicle, it is very difficult to obtain a satisfactory washing job by manual labor, in which the washing is done across the grain.

20 The object of my invention is to provide a machine for automatically washing the top of a motor vehicle, such machine being adapted by means of a gravity counter-balanced frame carrying washing or cleaning elements to automatically 25 adjust itself to the varying heights of a line of vehicles as they are successively moved along the said runway and under my washing machine, so that the top of each vehicle will be rapidly and thoroughly washed without attention from the 30 help, thereby creating a savings in labor costs and providing a more satisfactory job than possible by hand washing.

A further object of my invention is to provide such a machine also adapted to wipe the top of 35 the vehicle dry after it has been washed.

A still further object of my invention is to provide such a machine provided with means adapted 40 to automatically turn on the water or other fluid with which the vehicle is washed, as the forward end of the vehicle passes under the machine and to simultaneously actuate a revolving brush brought into contact with the vehicle top, and adapted, when the vehicle has passed from under 45 the machine, to automatically shut off the water and stop the brush from rotating.

A still further object of my invention is to provide such a machine adapted to be raised by manual means out of operative position without actuating the washing elements.

50 These and other incidental features of my invention, the details of construction, and the mode of operation are hereinafter fully described with reference to the accompanying drawings.

In the drawings:

55 Fig. 1 shows a side elevation of my machine and

illustrates a motor vehicle passing thereunder and in position to be worked upon;

Fig. 2 shows a view taken looking in the direction of the arrows 2 in Fig. 1, and illustrates the detail of the snubber element for restraining the downward movement of the operating elements of my machine;

Fig. 3 shows a top plan view of my machine and illustrates further details of construction;

Fig. 4 shows a perspective view of my machine;

Fig. 5 shows a side elevation of my machine and illustrates the motor vehicle being pulled thereunder by means of a traveling chain;

Fig. 6 shows a section taken on the line 6—6 of Fig. 1 and illustrates further details of construction;

Fig. 7 shows a section taken on the lines 7—7 of Fig. 6 and illustrates the details of the rotary brush and wiping means;

Fig. 8 shows a detail of the wiping means;

Fig. 9 shows a modification of my machine adapted to be entirely supported from the ceiling and adapted for vertical movement relative to the motor vehicle;

Fig. 10 shows a front elevation of the same;

Fig. 11 shows a top plan view of this modification of my machine; and

Fig. 12 shows diagrammatically, a further modification of my machine adapted for being moved in an inclined plane.

Referring now to Figs. 1 to 8, my machine for washing the tops of motor vehicles comprises a skeleton frame *a* adapted to have a motor vehicle *b* pass thereunder, as illustrated in Figs. 1, 4, and 5.

A supplementary, inclined frame *c* is connected at one end to the rear cross member *a'* by a universal joint *d*, permitting a pivotal movement of the frame in all directions. For the reason that when my invention is arranged for washing the tops of motor vehicles traveling on a circular track, the deflection of such travel from a straight line must be accommodated. The other end of the supplementary frame *c* is supported by cables *f* passing over pulleys *g*, *g'*, and connected to counter weights *h*, slidably mounted on the forward standards *a3* of the frame *a*. Removable segments *h'* are provided on the counter weights *h*, to permit the latter to be adjusted relatively to the weight of the supplementary frame *c*. By these means, the supplementary frame *c* is counter weighted so as to be easily lifted by the top of a motor vehicle passing thereunder and to bear with equal force on each vehi-

cle, whereby a uniform and thorough washing job will be performed on each vehicle, as hereinafter further described.

- Other cables *j*, are connected to the corners of 5 the forward end of the frame *c* and passed upwardly over pulleys *k*, supported on the cross member *a2* and joined at their ends at the center of the frame to form a single cable *j'*, which passes over pulleys *k'*, *k2*, supported on the rear 10 cross member *a'*, and the upper end of one of the rear standards *a4* of the frame *a* respectively, from where the cable *j'* is connected to a winch element *l* carried on the said standard *a4* in convenient reach from the floor. Adjustable 15 stops *j2* are provided on the cables *j* to limit the downward movement of the frame *c*. By these means, the frame *c* may be adjusted to any given height, or lifted into inoperative position, as may be desirable.
- 20 In addition to these means, a suitable snubbing element *m*, carried by the frame *a* is connected to the supplementary frame *c* at *m'* to prevent the latter from falling too rapidly after a vehicle has passed from under it.
- 25 A rotary brush *2* is transversely journaled on the forward end of the frame *c*. The brush *2* is driven by an electric motor *3*, see Figs. 3 and 6, also carried by the frame *c*, by means of a belt *4* and pulley *4a*. The pulley *4a* is carried 30 on a stub shaft *4b* of a suitable transmission *4c*, the driven shaft *5b* of which is provided with a sprocket *5c* connected by a chain *5* with a sprocket *6* mounted on the end of the shaft *7* of the brush *2*.
- 35 A switch *8* is provided in the circuit *9* of the motor *3*, the operating arm *8a* of which is normally held in open position by a cable section *12* connected to the upper transverse member *a2* of the frame *a*, but when the frame *c* is lifted by 40 a vehicle passing thereunder, the said cable section will become slack and a spring *10*, connected to said lever, will then draw it downward, thus closing the switch and actuating the motor and the brush to operate on the top of the car.
- 45 Similarly, to spray water on the vehicle top ahead of the brush, a transverse, perforated spray pipe *14* is mounted on the frame *c*, ahead of the brush *2*, which is supplied with water through suitable couplings *15*, connected to one of the side members *c'* of the frame *c*, the frame *c* being preferably constructed of pipe sections and the other end of the side member *c'* being connected to a source of water as at 16.
- 50 A valve *17* is provided in the coupling *15*, the operating handle *17a* of which is also engaged with the cable *j*, and is normally held in closed position when the said cable is taut, but when the frame *c* is lifted by a vehicle passing thereunder and becomes slack, a spring *18* will pull 55 the lever *17a* downward and open the valve and permit water to be sprayed onto the top of the car through the said perforated spray pipe *14*.
- Further, when the frame *c* is lifted by the winch element *l* so as to be out of contact with the top of a vehicle, as for example when an open vehicle is passed thereunder, the spray pipe *14* is shut off, since the cable *12* will become slack, but the motor *3* and brush *2* will be permitted to continue in operation, as the cable *j* will remain taut.
- In order that the top of the vehicle may be quickly wiped dry, a squeegee element *20*, carried by brackets *21*, is located in the rear of the brush and positioned to bear on the vehicle top *b'*, thus wiping it dry.

In order that the top of the vehicle will not be injured when it comes into contact with the supplementary frame *c*, regardless of its height, I have provided spaced, parallel bars *22* preferably three in number, secured to the rearward end of the frame *c* on a cross-member *c2* which are inclined downwardly, and supported from the forward end by bolt members *23*. The two outer bars are provided with a series of rollers *24*, and the center bar is provided with a series of similar rollers *24b*, arranged in staggered relation to the rollers *24* so that the forward end of the top of the vehicle will ride against a continuous anti-friction surface in lifting the frame.

In the operation of my machine, a vehicle is preferably drawn under the frame *a* by a traveling chain, as illustrated at *p* in Fig. 5, or by any other means that may be desirable.

As the vehicle progresses under the frame *a*, the front end of the top comes into contact with the rollers *24*, *24b*, and the supplementary frame *c* is lifted until the brush *2* comes into contact with the vehicle top, when the motor *3*, and therewith the brush *2*, and spray from the spray pipe *14* will be actuated, as before described, to wash the top of the car as it passes slowly under the brush, illustrated in Fig. 7. Then the squeegee element *20* will wipe the top of the car dry and prevent streaks or stains from remaining. The squeegee element *20* is adapted to limited vertical movement in a slot *21a* in the bracket *21*, so that as the brush *2* passes off the rear end of the top and falls slightly, the squeegee element may adjust itself to such change of position.

Finally, as the squeegee element *20* passes off the end of the vehicle, the frame *c* will move downward again, stopping the motor and spray, and my machine is then set for the next car, the downward movement of the frame *c* being restrained by the snubbing elements *m*.

Referring now to Figs. 9, 10, and 11, I will describe a modification of my machine adapted to be supported from the roof of the washing room and to be moved vertically.

This modification comprises a supporting bracket *30*, bolted to the roof in a desirable location, as over the runway, in which is slidably and rotatably journaled a shaft *31* to the lower end of which a frame *32* carrying the operative elements of this modification, is hingedly secured, 125 as at *31a*, for movement on a horizontal, transverse axis.

The shaft *31* of the frame *32* is supported by a cable *33* passing over pulleys *34*, *34a*, and connected at its other end to counter weights *35*, 130 whereby the frame *32* may be easily lifted by the forward travel of the top of the vehicle passing thereunder.

Furthermore, the frame *32* is vertically adjustable by means of a cable *36* connected to the cable *33* by a clamp *37*, which is passed over a pulley *35a* and secured at its other end to a winch *38* located on a suitable upright *38a* within convenient reach from the floor.

The frame *32* is provided with counter weights 140 39 adjacent its rearward end, by which the said frame is balanced to remain normally horizontal. Inclined arms *40* are provided carrying a series of rollers *41*, similar to those before described, adapted to guide the frame and brush 145 relatively to the vehicle top as it is lifted and to prevent the same from being injured as it comes into contact with the frame *32*.

The end of the frame *32* is provided with a rotary brush *42* journaled on a shaft *43* and driven 150

by means of a chain and belt 44, 44a, respectively, from an electric motor 45. A switch 46 is provided in the electric circuit 45a of the motor 45, the operating lever 46a of which is held in closed position when the frame is in its lowermost position, by means of a cable section 48 connecting it with the bracket 30, but when the frame is raised by a vehicle passing under it, the cable section becomes slack and a spring 50 pulls the lever 46a downward to close the switch and actuate the motor. Since the motor 45 is for convenience located at one side the frame, an adjustable counter weight 59 is provided on the other side, in order to hold it in a normally level position.

A perforated, transversely arranged spray pipe 51 is provided ahead of the brush, which is connected through couplings 51a with the source of the water 51b, or other washing fluid that may be used. A valve 53 is provided in the said coupling, the operating handle 53a of which is engaged in a chain section 54, connected between the bracket 30 and the coupling 51a. The end of the handle is also connected by a cable section 57 passed over a pulley 58, and connected with the cable 35.

By this construction, when the cable and chain are taut, the lever will hold the valve in closed position, but when the frame is lifted, it will become slack and a spring 53b will pull the lever downward opening the valve and causing the water to be sprayed on the top of the vehicle.

In Fig. 12, I have shown diagrammatically a further modification of my invention in which the supplementary frame 60 is supported on a carriage 61, adapted to be moved on an inclined track 62, by the top of the motor vehicle as it is moved thereunder. A counter weight 63 is connected to the carriage 61 by a cable 65 arranged over a pulley 66 secured at the upper end of the track. Another cable 67 is fastened to the carriage 61 and passed over pulleys 68, 69, and to a winch 70, by which the frame 60 is adjustable on the track or by which it may be moved to an operative position.

The frame 60 is otherwise similar to the frame 32, shown in Fig. 9, and is provided with a rotary brush 71 and spray 72. The operative and control means provided for this modification are similar to those above described, and are therefore not shown.

In this modification, the upward movement of

the frame 60 by the forward end of the top of the vehicle will be attained with somewhat less resistance. Also, in this form, the control means may be somewhat simplified. A hose 73 is connected with a source of water at one end and at the other to the spray 72, through the pipe section constituting the frame side, as before described.

I claim:

1. In an automobile washing machine, the combination of a gravity counter balanced vertically movable frame normally in lower position, a contact member carried by said frame, a cleaning element carried by the frame, said contact member arranged at an oblique angle with the horizontal when said frame is in its lower position, whereby the movement of an automobile under the said frame causes the top of the vehicle to abut with said contact member and lift the said frame into operative position. 85

2. A vehicle washing machine comprising a supporting member, a frame hingedly connected to said supporting member, a washing element carried by said frame, means carried by said frame adapted to have contact with the top of a vehicle passing under said frame, whereby to lift the frame into operative position. 90

3. A vehicle washing machine comprising a supporting member, a frame hingedly connected to said supporting member, a washing element 105 carried by said frame, means including a series of rollers carried by said frame adapted to have contact with the top of a vehicle passing under said frame, whereby to lift the frame into operative position. 110

4. In a mechanism of the character described, a pivotally mounted inclined frame suspended above an automobile runway, a brush rotatably mounted at one end of the frame crosswise of the runway, a motor secured to the frame and adapted 115 to rotate the brush, supporting means pivotally connected with the frame, and a guide secured to the under side of the frame and adapted to carry the brush on to the automobile top.

5. In a mechanism of the character described, 120 a vertically movable frame supported above an automobile runway, a driven brush rotatably mounted at one end of the frame crosswise of the runway, a guide secured to the under side of the frame and adapted to carry the brush on to 125 the automobile top.

OLIN M. KIGGINS.
